HANDLE GRIP FOR UPRIGHT VACUUM CLEANERS, FLOOR POLISHING MACHINES AND THE LIKE

Edward L. Verhagen, 314 Elm Ave., Rahway, N.J.

Filed Sept. 25, 1962, Ser. No. 71,845

Term of patent 14 years

(Cl. D9—2)

FIG. 4.

FIG. 1.

FIG. 2.

FIG. 3.

FIG. 5

FIGURE 1 is a top elevational view of a handle grip for upright vacuum cleaners, floor polishing machines and the like showing my new design.

FIGURE 2 is a side elevational view thereof.

FIGURE 3 is a bottom elevational view thereof.

FIGURE 4 is an elevational view as seen from above FIGURE 1.

FIGURE 5 is an elevational view as seen from below FIGURE 1.

I claim:

The ornamental design for a handle grip for upright

vacuum cleaners, floor polishing machines and the like, as shown.
